(57) **CLAIM**

The ornamental design for an aerosol generating device, as
shown and described.

DESCRIPTION

FIG. 1 is a front, top, and right side perspective view of a
first embodiment of an aerosol generating device showing
the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof.

FIG. 8 is another front, top, and right side perspective view
thereof shown in a position of use.

FIG. 9 is a front, top, and right side perspective view of a
second embodiment of an aerosol generating device showing
the new design.

FIG. 10 is a front elevational view thereof.

FIG. 11 is a rear elevational view thereof.

FIG. 12 is a top plan view thereof.

FIG. 13 is a bottom plan view thereof.

FIG. 14 is a left side elevational view thereof.

FIG. 15 is a right side elevational view thereof; and,
FIG. 16 is another front, top, and right side perspective view
thereof shown in a position of use.

The broken lines depict portions of the aerosol generating
device that form no part of the claimed design.
